DESIGN FOR A WOMAN'S JUMPER

Max Levitt, New York, N. Y.

Application February 5, 1944, Serial No. 112,455

Term of patent 7 years

(Cl. D3—26)

To all whom it may concern:

Be it known that I, Max Levitt, a citizen of the United States of America, residing at New York, in the county of New York and State of New York, have invented a new, original, and ornamental Design for a Woman's Jumper, of which the following is a specification, reference being had to the accompanying drawing, constituting a part thereof.

I claim:

The ornamental design for a woman's jumper, as shown and described.

MAX LEVITT.
